ELECTRICAL SWITCH HOUSING

Walter A. Wolf, Logansport, Ind., assignor to Switches,
Incorporated, a corporation of Indiana

Filed May 20, 1968, Ser. No. 12,001

Term of patent 14 years

Int. Cl. D13—03

U.S. Cl. D26—13

Fig. 3

Fig. 1

Fig. 2

Fig. 4

Fig. 5

FIGURE 1 is a fragmentary perspective view of the electrical switch housing embodying the new design;

FIGURE 2 is an end view of the electrical switch housing;

FIGURE 3 is a fragmentary top plan view of the electrical switch housing;

FIGURE 4 is a fragmentary side elevational view of the electrical switch housing; and

FIGURE 5 is a bottom plan view.

A portion of the electrical switch housing is shown since it has indeterminate length.

I claim:

The ornamental design for an electrical switch housing, substantially as shown and described.
